UNITED STATES PATENT OFFICE.

CHARLES ROBERTS, OF PHILADELPHIA, PENNSYLVANIA, ASSIGNOR TO HIMSELF, JAMES WHITALL, R. PEARSALL SMITH, JOHN MICKLE, JR., CHARLES A. TATUM, AND WILLIAM H. NICHOLSON, OF SAME PLACE.

DESIGN FOR A BOTTLE.

SPECIFICATION forming part of Design No. 12,140, dated January 18, 1881.

Application filed October 29, 1880. Term of patent 7 years.

To all whom it may concern:

Be it known that I, CHARLES ROBERTS, a citizen of the United States, residing in Philadelphia, Pennsylvania, have invented or produced a new and original Design for a Bottle, of which the following is a specification.

The nature of my design is fully illustrated in and by the accompanying drawings, in which Figure 1 is a front view of the bottle; Fig. 2, 10 a side view of the same; Fig. 3, a top view, and Fig. 4 a modification. The body A of the bottle is seven-sided, one side, *a*, being wider than the others—a feature which must be observed in my design, although 15 the remaining sides may be more or less than six in number. All the sides excepting the side *a* merge directly into the rounded shoulder *b* of the bottle, which terminates at the base of the cylindrical neck *d*, the latter hav-

ing the usual lip *e*; or the sides may terminate 20 at a shoulder, as shown in Fig. 4. The flat portion of the wide side *a* has the arched upper termination, *f*, where the said side merges into or terminates at the shoulder.

I claim—

The within-described design, the same consisting of the body A of a bottle having many sides, one of which is wider than the others, all as described, and illustrated in and by the accompanying drawings.

In testimony whereof I have signed my name to this specification in the presence of two subscribing witnesses.

CHAS. ROBERTS.

Witnesses:

JAMES F. TOBIN,
HARRY SMITH.
